UNITED STATES PATENT OFFICE.

EDWARD CURRIER, OF FALL RIVER, MASSACHUSETTS.

KEROSENE-OIL BURNER.

Application filed June 8, 1923. Serial No. 644,199.

To all whom it may concern:

Be it known that I, EDWARD CURRIER, a citizen of the United States, residing at Fall River, in the county of Bristol and State of Massachusetts, have invented a new and useful Kerosene-Oil Burner, of which the following is a specification.

This invention aims to provide a device for converting kerosene oil or other liquids into gas, the gas being ignited and burning to produce the necessary heat, novel means being provided for controlling and regulating the heat, and novel means being provided for screening the fuel during its passage to the combustion orifice.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:

Figure 1 shows in side elevation, a device constructed in accordance with the invention; Figure 2 is a bottom plan; Figure 3 is a section on the line 3-3 of Figure 2; Figure 4 is a section on the line 4-4 of Figure 2; Figure 5 is a section on the line 5-5 of Figure 3; Figure 6 is a transverse section showing a portion of the combined spreader and screen delineated in Figure 5.

In carrying out the invention, there is supplied a bowl or body 1. A three-armed support 2 is secured to the upper edge of the bowl 1. An adjusting device 3 preferably a screw, is mounted in the support 2. A conical baffle 4 is disposed in the bowl 1 at the upper end thereof and has an upstanding marginal flange 5 spaced from the inner wall of the bowl. Nuts 6 secure the apex of the baffle to the lower end of the screw 3. By rotating the screw 3 in the support 2, the baffle 4 may be raised and lowered for adjustment, the baffle being held in any position to which it may have been adjusted, through the instrumentality of a nut 7 threaded on the upper end of the screw and

adapted to engage the support 2. The bowl 1 has an opening 8 in its bottom.

A retort, in the form of a coil 9 is located in the bowl 1. The inlet end 10 of the coil extends downwardly and laterally, out of the opening 8 in the bottom of the bowl as does the outlet end 11 of the coil. Clips 12, engaging the members 10 and 11, hold them on the bowl 1.

A union 14 is connected to the outlet end 11 of the coil 9. To one member of the union 14, a nipple 15 is threaded. The nipple 15 is threaded into one end of a T-coupling 16. Into the outer end of the T-coupling 16, a nipple 17 is threaded. A tubular screen 18 is mounted removably in the nipples 15 and 17 and is spaced thereby from the bore of the coupling 16 as shown in Figure 4. Intermediate its ends, the screen 18 has perforations 19 located opposite to the transverse branch of the coupling 16. At its outer end, the screen 18 is supplied with a flange 20 abutting against the outer end of the nipple 17. A cap 21 is threaded on the outer end of the nipple 17 and, engaging the flange 20 of the screen 18, holds the screen in place removably.

A pipe 22 is located between the members 10 and 11 in parallel relation thereto. The pipe 22 is threaded into one end of a T-coupling 23 disposed opposite to the T-coupling 16. The transverse branches of the couplings 23 and 16 are united by a connection 24. A nipple 25 is threaded into the outer end of the T-coupling 23. A cap 26 is threaded on the outer end of the nipple 25. The inner end of the pipe 22 is threaded into a coupling 27, at one end of the coupling. Into the other end of the coupling 27 a nipple 28 is threaded. A valve seat 29 is located in the coupling 27 and is held thereby by the nipple 28. The seat 29 has a central opening 30. The opening 30 is controlled by a needle valve 31 threaded into the nipple 25.

Passing to the burner portion of the device, it is to be observed that the inner end of the nipple 28 is threaded into a T-coupling 32. Into the outer end of the T-coupling 32 a nipple 33 is threaded. A tubular screen 34 is located removably in the nipples 28 and 33. The screen 34 has perforations 35 located opposite to the transverse branch of the T-coupling 32. The screen 34 is spaced by the nipples 33 and 28 from the

bore of the T-coupling 32, as shown in Figure 3. The transverse branch of the T-coupling 32 extends upwardly through the opening 8 in the bore 1. At its outer end, 5 the screen 34 has a flange 36. The flange 36 abuts against the outer end of the nipple 33. A cap 37 is threaded on the outer end of the nipple 33. The cap 37 engages the flange 36 of the screen 34 and holds the screen 10 removably in place. A vertical casing 38 is threaded into the transverse branch of the T-coupling 32 and extends upwardly into the bowl 1 at the axis thereof. A cap 39 is threaded on the upper end of the casing 38. 15 The cap 39 has a central burner orifice 41. Within the casing 38 is located a combined spreader and screen. The combined spreader and screen comprises a tubular stem 42 carrying an upper disk 43 and any 20 desired number of lower disks 44. The disks 43 and 44 have perforations 45. The upper disk 43 rests on the upper end of the casing 38, the lower disks 44 being received in the casing. A rod 46 is mounted for 25 limited reciprocation in the tubular stem 42. At its upper end, the rod 46 has a head 47. A securing element 48 is mounted in the lower end of the rod 46 and is spaced from the lower end of the tubular stem 42. 30 The fuel proceeding through the inlet end 10 of the coil 9, traverses the coil and in the coil the fuel is thus formed wholly or in part into gas, by the flame proceeding from the burner orifice 41. The fuel leaves the 35 coil 9 by the outlet end 10, and as the fuel traverses the screen 18, foreign matter in the fuel is removed. The fuel passes into the pipe 22 through the connection 24 and the T-coupling 23. The flow of the fuel 40 through the opening 30 in the valve seat 29 is regulated by the needle valve 31. The tubular screen 34 exercises its obvious function as the gas or fuel passes into the casing 38. Here the gas is screened again and 45 is fed and distributed, by passing through the perforations 45 of the disks 44 and 43. The gas emerging through the burner orifice 41 in the cap 39 is ignited and produces a flame within the bowl 1, the retort or 50 coil being heated. The flow of the products of combustion upwardly and out of the bowl 1 may be regulated by raising and lowering the baffle 4 as hereinbefore explained. By removing the cap 37, the 55 screen 34 may be extracted for cleaning. Similarly, by removing the cap 21, the screen 18 may be withdrawn. When the cap 26 is detached, the needle valve 31 may be adjusted by means of a screw driver applied to the outer end of the needle valve. 60 When the cap 39 is removed, the rod 46 may be pulled upwardly by the head 47 until the securing element 48 abuts against the lower end of the stem 42, the rod thus 65 serving as a handle whereby the spreader

or screen comprising the elements 42, 43 and 44 may be lifted out of the casing 38.

Briefly considered, and generally reviewed, the device embodies, among other combinations a bowl 1, a coil 9 in the bowl 70 and having an inlet end 10 and an outlet end 11, the outlet end having a return branch 22, a burner 28-29 on the return branch and discharging into the bowl, a spreader and screen 42-43 in the burner, 75 a tubular screen 34 in the return bend and removable endwise therefrom, the screen cooperating with the burner, a second tubular screen 18 in the outlet and removable endwise therefrom, the second 80 screen being located at the place of juncture between the outlet and the return branch, a seat 29 in the return branch, a valve 31 in the return branch and adapted to cooperate with the seat to regulate the 85 flow of fuel through the seat, a baffle 4 in the bowl, above the coil and the burner, and means 3 for adjusting the baffle toward and away from the coil and the burner. 90

What is claimed is:

1. In a device of the class described, a bowl, a coil in the bowl and having an inlet end and an outlet end, the outlet end having a return branch, a burner on the return branch and discharging into the bowl 95 a tubular screen in the return branch and removable endwise therefrom, the screen cooperating with the burner to remove foreign matter from the fuel immediately before the fuel proceeds to the burner, a tubular screen in the outlet and removable endwise therefrom, the last specified screen being located at the place of juncture between the outlet and the return branch, and a valve in the return branch and controlling 100 the flow therethrough.

2. In a device of the class described, a bowl, which decreases in diameter from its upper end to its lower end, the bowl being provided with a reduced opening in its 110 lower end, a coil in the bowl and having an outlet end and an inlet end, both of which extend downwardly through the opening and laterally on the outside of the bowl, the outlet having a return branch extended beneath the opening, a burner on the return branch and extended upwardly into the bowl through the opening and located within the coil, and means for controlling 115 the flow of fuel through the coil. 120

3. In a device of the class described, a bowl which decreases in diameter from its upper end to its lower end, the bowl being provided with an opening in its lower end, a coil in the bowl and having an inlet end 125 and an outlet end, both of which extend downwardly through the opening and laterally on the outside of the bowl, the outlet having a return branch extended beneath the opening, a burner on the return 130

branch and extended upwardly into the bowl through the opening, a conical baffle in the upper end of the bowl and provided with an upstanding flange, and means for adjusting the baffle in a direction substantially parallel to the flange.

4. In a device of the class described, a burner comprising a casing, a cap on the casing and provided with a burner orifice and a screen and spreader including a tubular stem and spaced disks thereon, one disk engaging the casing and the other disk being located in the casing, the disks being

perforated, and a handle for lifting the screen, and spreader out of the casing, the handle being slidable longitudinally in the stem to render the stem accessible when the cap is removed. 15

In testimony that I claim the foregoing as my own, I have hereto affixed my signature in the presence of two witnesses. 20

EDWARD CURRIER.
